UNITED STATES PATENT OFFICE.

JAMES F. SMITH, OF GAFFNEY, SOUTH CAROLINA.

LUG-STRAP SUPPORT.

1,339,295.

Specification of Letters Patent. Patented May 4, 1920.

Application filed December 22, 1919. Serial No. 346,474.

To all whom it may concern:

Be it known that I, JAMES F. SMITH, a citizen of the United States, residing at Gaffney, in the county of Cherokee and State of South Carolina, have invented new and useful Improvements in Lug-Strap Supports, of which the following is a specification.

This invention comprehends the provision of an attachment for the picker arm of a loom, the attachment being designed to reinforce the arm with a view of preventing breakage of the latter, or undue wear of the same, and also designed to maintain the lug strap operatively positioned upon the arm.

The nature and advantages of the invention will be better understood when the following detail description is taken in connection with the accompanying drawing the invention residing in the construction, combination and arrangement of parts as claimed.

In the drawing forming part of this specification like numerals of reference indicate similar parts in the several views and wherein:

Figure 1 is a side elevation of a portion of a picker arm showing the attachment associated therewith.

Fig. 2 is a transverse sectional view taken on the line 2—2 of Fig. 1.

Fig. 3 is a perspective view of the attachment.

Referring to the drawing in detail, 10 indicates the picker arm of a loom, 11 the strap for the lug, while the attachment is indicated generally at A and clearly illustrated in Fig. 3.

The attachment is in the form of a clamp adapted to embrace the picker arm 10 and is constructed of metal for the purpose of reinforcing the arm with a view of preventing breakage thereof or undue wear of the same, by constant impact between the arm and the lug strap. The clamp is shaped to provide spaced upper and lower U-shaped portions 12 and 13 respectively, both of which portions project in a common direction from the body portion 14 of the clamp which connects these portions together. The U-shaped portion 12 is of a greater depth than the U-shaped portion 13, as this portion of the clamp is designed to support the lug strap 11 in a manner whereby the strap is prohibited from coming in contact with the

picker arm 10. Both the U-shaped portions 12 and 13 respectively embrace the arm 10 in a manner whereby the body portion 14 of the clamp lies against the rear edge 60 of the arm, the U-shaped portions projecting beyond the forward edge of the arm and having their extremities connected by means of bolts and nuts, or other suitable fastening means indicated at 15. The body 65 portion 14 of the clamp is provided with an aperture 16, which receives a pin or the like 17 projecting from the rear edge of the arm 10 to prevent the clamp in its entirety from 70 slipping downwardly upon the arm 10 when it is in its applied position.

The opposed sides of the U-shaped portion 12 are bent from their lower edges to provide hook-like supports 17 for the lug strap 11, the parallel limb of this strap 75 being arranged for sliding movement within the hook-like members. Each hook comprises a base 18 and a vertically disposed member 19, spaced from the adjacent side of the U-shaped portion 12, of which it 80 forms a part. The opposite ends of the base 18 of each hook-like member are curved downwardly, while the vertically disposed portion 19 of each hook like member has its opposite ends curved outwardly so that the 85 ends of the base and vertically disposed portion are prevented from scraping against the lug strap during the operation of the latter. Formed on the upper end of the clamp is a transversely disposed member 90 20 which projects beyond the opposite sides of the arm 10 and disposed at an angle with respect to the rear edge of the arm as shown. This transverse member 20 co-operates with the hook-like members 17 to 95 prevent the lug strap from jumping or moving out of the attachment as will be readily understood. While the U-shaped portion 12 prevents the parallel limbs of the lug strap from coming in contact with the picker arm 100 10, so also does the body portion 14 prevent the end of the strap 11 from coming in contact with the rear edge of the arm. Consequently the arm is materially strengthened, and protected from undue wear incident to 105 the impact between the said arm and said lug strap.

While I have shown and described what I consider the preferred embodiment of the invention, I desire to have it understood 110 that I do not limit myself in this connection, and that such changes may be resorted

to when desired as fall within the scope of what is claimed.

Having thus described my invention what I claim as new is:—

- 5 1. The combination with a picker arm and lug strap, of an attachment for said arm comprising a member designed to brace the arm, means formed on the sides of said member for supporting the lug strap, and
10 10 an extension formed on the front of said member and coöperating with the said means for preventing the lug strap from being casually separated from said member.
- 15 2. The combination with a picker arm and lug strap, of an attachment for said arm comprising a member designed to embrace said arm, opposed hooks carried by the sides of said member for supporting the lug strap and an extension projecting from
20 20 the front of said member above said strap and coöperating with said hooks to prevent the strap from being casually separated from the member as specified.
- 25 3. The combination with a picker arm and lug strap, of an attachment for said arm comprising a member designed to embrace the arm, opposed hooks formed on the sides of said member for supporting the lug strap, an extension projecting from said
30 30 member and arranged above the strap, the front of said extension coöperating with the hooks to prevent the strap from being casually separated from the member, and a bottom and vertical portion of each hook having their ends curved away from said strap for the purpose specified.

4. The combination with a picker arm and lug strap, of an attachment for said arm comprising spaced U-shaped members embracing said arm, a strip connecting the 40 U-shaped members, and arranged to engage one edge of said arm, and means for securing the U-shaped members in position above the arm, opposed hooks carried by one of said U-shaped members, and constituting a 45 support for said lug strap, and an extension projecting from said U-shaped member above said strap, said extension coöperating with the hooks to hold the strap operatively positioned upon the arm. 50

5. The combination with a picker arm and lug strap, of an attachment for said arm comprising spaced U-shaped members, embracing said arm, a strip connecting the U-shaped members and arranged to engage 55 against one edge of the arm, said strip having an opening, a lug projecting from said arm through the opening to prevent the attachment from moving longitudinally of the arm, means for holding the U-shaped portion about said arm, opposed lugs carried by one of said U-shaped portions and constituting a support for said lug strap, and an extension projecting from said U-shaped portion and disposed with respect to said hook and strap to coöperate 60 with the hooks to prevent the strap from becoming casually separated from said attachment. 65

In testimony whereof I affix my signature. 70

JAMES F. SMITH.
